ATTORNEY

UNITED STATES PATENT OFFICE

FRIEDRICH BROEKER, OF FURSTENWALDE, GERMANY

STEAM-DRYING OR WATER-SEPARATING APPARATUS FOR STEAM-POWER PLANTS

Application filed May 24, 1928, Serial No. 280,364, and in Great Britain April 12, 1928.

In existing steam boiler plants there is the known disadvantage that, in conducting away the steam, liquid is entrained so that a wet or moist steam is used for driving the power plant. The consequence of this is that condensed water which is deposited in large quantities sets up a counteraction and in starting and driving the engines damage may be done, such as fracturing the top of the piston, unsealing the stuffing box glands, pipe lines and so forth. A large reduction in steam pressure leads to a large coal consumption or oil consumption as well as a large amount of wear of the stuffing box material and heavy strains on the materials in general.

The essence of the present invention consists in that the steam produced in the boiler is used as dry steam, this being effected without super heating the steam but by separating out the quantities of hot liquid from the steam to be used for power purposes. On the respective sides of the man-hole which is disposed between the steam dome and the steam space of the boiler are provided, suitably spaced from the boiler shell, two superposed water separating plates having different diameters. If the valve of the steam supply pipe is open the water boiling in the boiler is entrained by the steam pressure and the vacuum pressure produced in the supply pipe. The steam which flows from the boiler to the dome strikes against the separating plates so that the entrained water is thrown down. The steam is now partially dried and endeavours to flow into the steam pipe connected to the dome. The steam pipe is however formed with an elbow piece which projects into the dome and has at the end an enlarged tubular portion with a protecting hood and steam inlet apertures disposed there beneath. In the outer wall of the tube are provided horizontally extending pressure or steam separating fins whereby the entrained water is completely separated out so that now a completely dry steam is provided for driving the prime movers.

In a boiler plant which is subjected to heavy demands it has been found from tests that the saving in quantities of coal, oil,

grease and packing material is very substantial.

It is possible to install the apparatus in any boiler plant, since by the provision of hinges the water separating plates can be passed through the manhole opening in a collapsed condition.

The subject of the invention is illustrated by way of example in the accompanying drawing wherein: Fig. 1 is a longitudinal section through the steam drying or water separating device (steam trap) built into a boiler.

Fig. 2 is a longitudinal section through the steam dome with manhole and steam drying and water separation device fitted in.

Fig. 3 is a plan of the water separating plates connected in hinged form and to be fitted into the manhole.

Fig. 4 is a cross-section of the water separating plates fitted on the respective sides of the manhole, the hinge arrangement of the two parts of each plate being apparent.

Fig. 5 is a cross-section of the two part water separating plates fitted on the respective sides of the manhole.

Above and below the boiler shell plate *b* of the manhole *a* which lies between the dome *c* and the boiler chamber *d* there are mounted at suitable distances, water separating plates in two parts connected together. The upper two part plate *k*, *l* which covers the manhole *a* is connected by pin joint by means of inside hinges *w* so that the two plates *k*, *l* can be folded together in order to admit of passing them through the manhole *a* for fitting in. To this straight abutting edge of the cover plate *k* there is riveted on top or outside a stop bar *g* running right through so that the second hinged plate *l* is provided with a stop on the inner face of the stop bar *g* and therefore cannot be tilted upwards. The two plates *k*, *l* when in the stretched and extended position after erection assume a rigid horizontal position above the manhole *a*. The water separating plates *e*, *f*, in two parts are also connected inside with the hinge bands *h* and provided outside as described above with a stop bar *g* so that the two plates, *e*, *f* in the extended position also form a rigid horizontal

plate which cannot be tipped downwards. To the two top water separating plates *k* and to the two bottom connected water separating plates *e*, *f*, there is fixed on the inner surface 5 a two part ring *m* or *n* with a number of steam passage slots *o* in such manner that it is possible to fold together the two interconnected water separating plate parts. The bottom faces of the annular parts *m* or *n* stand loosely on the faces of the boiler shell plate *b*. When the top two part boiler separating plates *k*, *l*, has been passed through the manhole *a* into the dome *c* then the screw bolt *i* is screwed firmly by means of a spanner into 10 the upper stop bar *g*. Then the bottom water separating plate *e*, *f*, with stop bar *g* riveted on is slipped over the screw bolt *i* and screwed up by means of washers, nuts and lock-nuts in such manner that the top and bottom hinge 15 connected water separating plates *k*, *l* and *e*, *f*, form a rigid construction suspended over the manhole.

The two water separating plates *e*, *f*, and *k*, *l*, are each provided with two valve discs *p* 20 under spring action which serve for the purpose of allowing the steam to pass without hindrance through the plate valves *p* from the steam generating chamber *d* to the steam dome *c* in case of any choking up of the wa- 25 ter passage slots *c* against the two rings *m*, *m*, being produced by boiler scale etc. during the generation of steam. This construction of water separating plates produces the effect that the steam which is saturated with 30 water is compelled to impinge on many points in order thus to separate the water which it carries.

The steam eduction pipe, *q''* provided on the dome *c* is adjoined inside the steam dome 40 *c* by a long sweep bend *r* which serves to take the tubular extension *s*, the diameter of which varies and which is covered at the top by a hood *t*. The slots *u* arranged below the hood *t* serve as steam inlet apertures for the steam 45 pipe *r*, *q''*. The outer wall of the tubular member *s* is provided with a number of water separating plates or fins *v* of different diameters. The steam drawn off through the steam pipe *q''* strikes against the stepped 50 arrangement of separating plates *v* and the steam to be dried rebounds several times against the separating plates *v*, so that the entrained water is completely removed and dry steam only passes through the supply 55 pipe *q* to the prime mover.

I claim:—

1. In steam drying and water separating apparatus, a steam generator having a steam dome, a manhole beneath said dome, two 60 divided plates of different diameter, one arranged above and the other below said manhole, hinges joining the divided parts of each of said plates, rings spacing said plates and located one above and one below the manhole, 65 steam apertures in said rings, and pressure

bars for assisting to secure said plates rigidly in their opened out position.

2. In steam drying and water separating apparatus, a steam generator having a steam dome, a manhole beneath said dome, two divided hinged plates, one located above and the other below said manhole, a ring spacing each of said divided plates, steam apertures in said rings, means for fixing said plates rigidly in their extended position and spring controlled disk valves carried by said plates constituting safety by-passes for the steam if the apertures in said spacing rings become choked.
